UNITED STATES PATENT OFFICE.

HYMAN KOPPEL, OF BOSTON, MASSACHUSETTS.

ASH-SIFTING APPARATUS.

1,226,976.

Specification of Letters Patent. Patented May 22, 1917.

Application filed November 11, 1916. Serial No. 130,923.

To all whom it may concern:

Be it known that I, HYMAN KOPPEL, a subject of the Czar of Russia, and resident of Boston, in the county of Suffolk and State of Massachusetts, have invented new and useful Improvements in Ash-Sifting Apparatus, of which the following is a specification.

This invention relates to an ash sifting apparatus and its object is to provide a new and improved device which may be directly connected to or combined with a range or other heater for sifting ashes and separating out the coarser or partly consumed particles of the fuel without handling the ashes or first removing them from the range.

In the drawings hereto annexed which illustrate certain embodiment of the invention,—

20 Figure 1 is an elevation of a range or stove of the type having an open base supported on legs with the ash sifting apparatus shown partly in elevation and partly in section;

25 Fig. 2 is an enlarged cross section of the ash sifting apparatus shown in Fig. 1;

Fig. 3 is an elevation of a range or stove of the type having a closed-in or incased base extending to the floor with a modified form of ash sifting apparatus adapted to such form of range;

30 Fig. 4 is a plan view, partly in horizontal section of the ash sifting apparatus shown in Fig. 3; and

35 Fig. 5 is a detail illustrating a locking device for the split bearing hereinafter described.

Referring first to the form of the invention shown in Figs. 1 and 2, which is adaptable to an ordinary stove, A represents the stove or range having an open base supported on legs. 1 is the casing of the ash sifting apparatus closed on four sides and open at the top, fitted to the range immediately below the fire box a and the usual shelf b.

Within the casing is the sifter consisting of a rotary drum-like sieve journaled on a horizontal axis. The sieve is preferably in the form of a complete cylinder having solid end walls 2, 2, and cylindrical open-work side walls 3 made of wire mesh or other suitable grating or mesh material. The end walls, 2, 2, are provided with trunnions 4 and 4^a journaled in suitable bearings in the walls of the casing 1.

The sieve has a removable section whereby the sieve body may be opened for the admission or discharge of its contents, or closed for the sifting operation. The removable section preferably consists of a segment 3^a of the cylindrical sieve, taken on a plane intersecting both the cylindrical side walls and the flat end walls. A sliding connection is provided between the removable section and the body of the sieve, consisting of the channeled slideways 5, 5, extending along the sides of the opening in the sieve, and the flanges 6, 6, on the edges of the removable section fitting in the channeled slideways 5.

A door 7 hinged to the casing 1, and when closed constituting a part of the upper end wall of the casing, affords an opening for the removal and insertion of the removable section 3^a which may be slid endwise through the door opening.

The bearing for the outer trunnion 4 of the sieve is split, as best shown in Fig. 5, and is located partly in the fixed wall of the casing and partly in the lower edge of the door 7, which swings under the shelf b, so that when the door is opened the trunnions are disengaged from their bearings and the sieve may be removed bodily through the top of the casing. The lower bearing section, 28, secured to the wall of the casing 1, is provided with a pair of locking sockets 25, and the upper section 27 has a pair of lugs or ears 26 which fit into the sockets 25 when the door 7 is closed. Thus the split bearing is held firmly closed on the trunnion 4 while the sieve is operated. A pinion 8 is fixed to the trunnion 4 and meshes with a relatively large gear wheel 9 which is journaled on the inner side of the outer end wall of the casing. The axle of gear 9 extends through the wall of the casing and is provided with a square socket into which the squared end of key or crank 10 fits at the outside of the casing. The trunnion 4 on the outer end of the sieve is similarly provided with a square socket to receive the key or crank so that the sieve may be rotated either through the gear 9 for rapid rotation, or directly through the trunnion 4 for slow rotation or for reciprocation.

In the lower part of the casing 1 underneath the rotary sieve is an ash pan or drawer 11 which may be withdrawn or inserted through an opening in the end wall

of the casing. Inclined strips 12 secured to the walls of the casing form ledges to prevent the ashes which come down from the sieve from passing into the crevices between the sides of the drawer and the casing walls.

A pair of downwardly inclined ledges or chutes 13 are secured to the upper part of the walls of the casing and terminate in proximity to the sides of the opening in the sieve when the section 3^a is removed, and the sieve is rotated to bring the opening to the top. These ledges direct the ashes from the fire-box into the sieve but do not interfere with the complete rotation of the sieve when the removable section is replaced. In order to facilitate the removal of the sieve from the casing, the ledges 13 may be hinged as at 14 to permit them to be folded upward and backward, thereby affording sufficient clearance to permit the sieve to be bodily removed through the top of the casing.

Referring now to the form of the invention shown in Figs. 3 and 4: A' represents a stove or range the base of which is inclosed or incased down to the floor. The casing 1^a of the ash sifting device is a part of the stove casing itself. The rotary cylindrical sieve 3 with its removable section 3^a and sliding connections 5-6, are the same as before. The ledges 13^a, 13^b correspond to the ledges 13, 13 in Fig. 2 save that they are not hinged because the sieve cannot be lifted out through the top of the casing which is an integral part of the range.

The inner end of the sieve is supported on a trunnion 4^a, as before, journaled on the wall of the casing. The outer end of the sieve has a square hub which fits into a square socket piece 14 on a short shaft 15 which is journaled in the end of bracket 16. The bracket 16 is hinged to the casing at 17 to swing forward and outward and is normally urged toward its inward or operative position by a spring 24. The pinion 18 is fixed to the short shaft 15, and a relatively large gear 19 journaled by a short shaft 20 on the bracket 16 meshes with pinion 15. The short shafts 15 and 20 are each provided with square sockets into which the squared end of a key or crank 10 may be fitted for manually actuating the sieve. A door 21 hinged to the casing closes the end of the casing and is provided with apertures 22 and 23 registering respectively with the shafts 15 and 20. These shafts project into the apertures 22 and 23 and are readily accessible for the application of the crank or key from the outside when the door 21 is closed. When the door 21 is open and the bracket 16 is swung outwardly from the sieve, the sieve bearings will be disengaged and the sieve may be removed bodily through the open door.

The operation of the device in either form

is substantially the same. When the sieve is to be filled with ashes from the fire box, the removable section 3^a is removed endwise through the open door 7 or 21, and the door is then closed to prevent the escape of dust. The ashes are then dumped down into the sieve body through the open top, the sieve having been rotated to bring the opening to the top. The removable section 3^a is then replaced, and with the door of the casing closed the sieve is rotated or agitated by the key or handle 10, which may be applied either to the shaft of the large gear for rapid rotation of the cylinder or directly to the trunnion of the sieve for slower rotation or agitation. The finer ashes are thus shaken out of the sieve and fall into the drawer or ash pan 11, while the coarser particles remain in the sieve. It will be understood that this operation is performed while the door 7 or 21 is closed thus preventing the escape of dust into the room. The ash pan 11 may be then withdrawn, emptied and replaced, and by again removing the section 3^a of the sieve and rotating the sieve until the opening is brought to the bottom, the coarser or partly consumed particles may be dumped into the pan 11.

I claim:

1. An ash sifting apparatus comprising a casing, a drum-like sieve rotatably mounted in the casing with its axis disposed approximately horizontally, one peripheral side of the sieve having an opening for transferring ashes to and from the sieve, guides disposed longitudinally of the drum on opposite sides of the opening, a cover for said opening slidably mounted in the longitudinal guides, and a door in one end of the casing, the door being in alignment with the guides when the opening side of the sieve is approximately in uppermost position with respect to said horizontal axis so that said cover may be inserted or removed through the doorway without disturbing the contents of the sieve.

2. In ash sifting apparatus adapted to be inserted under the fire-box of a stove or the like, the combination of a casing, a drum-like sieve rotatably mounted in the casing with its axis disposed approximately horizontally, one peripheral side of the sieve having an opening for transferring material to and from the sieve, a cover for the opening, means for detachably mounting the cover on the sieve over the opening, and a door in one axial end of the casing, the door being disposed in part above the axis of the sieve so that said cover may be longitudinally inserted or removed through the doorway between the axis and fire-box when said opening is in an upper position.

3. An ash sifting apparatus comprising a casing, a rotary drum-like sieve journaled in the casing having a removable section, a

door in the upper part of one end wall of the casing, a split bearing for one end of the sieve, one section of the bearing being in the lower edge of the door and the other section in the upper edge of the adjacent wall, and coöoperating means on the door and wall for automatically locking and unlocking the two sections of the bearing to and from each other when the door is closed and opened respectively so that when the door is closed the two sections of the bearing are rigidly secured together.

4. An ash sifting apparatus comprising a casing, a rotary drum-like sieve in the casing, a door pivotally mounted on the casing to swing about an axis transversely disposed relatively to the axis of the sieve, a split bearing for the sieve, one section of the bearing being in the door and the other section being in the adjacent wall, and interlocking means on the door and casing arranged automatically to lock and unlock the two sections of the bearings to and from each other as the door is swung closed and open, respectively, about its transverse axis.

5. An ash sifting apparatus comprising a casing, a rotary drum-like sieve in the casing, the casing being divided at one end along a line extending approximately through the axis of the sieve, the portion of the casing on one side of said line being movable with relation to the other portion longitudinally of the axis of the sieve, an axial journal on the sieve, a split bearing for the journal, the two sections of the bearing

being disposed on the said portions of the casing, respectively, and means disposed on the respective portions of the casing for locking the two sections of the bearing together, the locking means being arranged to telescope 40 when the movable portion of the casing is moved into normal position longitudinally of the sieve axis.

6. An ash sifting apparatus comprising a casing, a sieve rotatably mounted in the casing, the sieve having a peripheral opening through which ashes may be dumped when the sieve is rotated into the position wherein the opening is disposed upwardly, and ledges on the inside of the casing extending 45 inwardly from the walls of the casing to the opening in the sieve, the ridges being movably mounted at least in part so that they may be adjusted relatively to the sieve.

7. An ash sifting apparatus comprising a 55 casing, a sieve rotatably mounted in the casing, the sieve having a peripheral opening through which ashes may be dumped when the sieve is rotated into the position wherein the opening is disposed upwardly, and ledges 60 on the inside of the casing extending inwardly and downwardly from the walls of the casing to the opening in the sieve, the ledges at least in part being pivotally mounted so that they may be swung outwardly in 65 such manner as to permit the sieve to be passed therebetween.

Signed by me at Boston, Massachusetts,
this fourth day of November 1916.

HYMAN KOPPEL.
